UNITED STATES PATENT OFFICE.

HARRY M. BELL, OF HOUSTON, TEXAS.

INDICATOR.

No. 906,679.

Specification of Letters Patent.

Patented Dec. 15, 1908.

Application filed January 21, 1907. Serial No. 353,405.

To all whom it may concern:

Be it known that I, HARRY M. BELL, a citizen of the United States, residing at Houston, in the county of Harris, State of Texas, have invented certain new and useful improvements in Indicators; and I do hereby declare the following to be a full, clear, and exact description of the invention, such as will enable others skilled in the art to which it appertains to make and use the same.

This invention relates to new and useful improvements in indicators for cars, and it has particular reference to an indicator for street cars in which are embodied means for moving a belt for displaying the names of the streets and means for simultaneously moving a belt having advertising matter printed thereon.

In connection with an indicator of the above type the invention aims as a primary object to provide a novel construction, combination and arrangement of parts, the details of which will appear in the course of the following description, in which reference is had to the accompanying drawings forming a part of this specification, like characters of reference designating similar parts throughout the several views wherein:

Figure 1 is a side elevation illustrating the housing of an indicator constructed in accordance with the present invention, parts being indicated by dotted lines. Fig. 2 is a front elevation, the front wall of the housing being broken away and illustrating the mechanism contained therewithin. Fig. 3 is a perspective view of a supporting base for such housing. Fig. 4 is a diagrammatic view illustrating the mechanism for operating the indicating system. Fig. 5 is a front elevation of the housing embodied in the invention, showing more particularly the manner of displaying printed matter through the windows thereof. Fig. 6 is a section on the line 8—8 of Fig. 2.

Referring specifically to the accompanying drawings, the numeral 1 designates a supporting base which is secured to the wall of the car by means of fastening bolts or screws 2 arranged at suitable intervals and which has formed at one side thereof a brace wall 3 coöperating with one of the side walls of the housing above referred to, to afford a support for the elements of the transmission gearing, the wall 3 with this object in view being constructed with bearings 4. The base

is formed with parallel dove-tail transverse grooves 5, in which are received conformable tongues 6 provided on the rear wall of the housings 7 and 7'. Such housings are constituted of substantially rectangular boxes having inwardly inclined front walls 8 and 8' which are formed with glass windows 9 and 9' through which the printed matter on the advertising and indicator belts is displayed.

The side walls of the housings and the wall 3 constitute bearings for transverse parallel shafts 13, 14, and 15 and 13', 14' and 15'. The shafts 13 and 14 and 13' and 14' are mounted adjacent to the rear wall of the housings and carry respective winding reels 16 and 17, and 16' and 17'. The shafts 13 and 14 project through the inner side wall of the housings 7 and 7' and are provided with splines 11 which engage in grooves 12 in the respective shafts 13' and 14'. In like manner the shafts 15 and 15' which are disposed adjacent the front walls 8 and 8' carry spools 18 and 18' which constitute guides for the respective indicator and advertising belts 19 and 20, the latter being wound about the respective pairs of reels 16 and 17 and 16' and 17' and having parallel movement. The shafts 13 and 14 have fast connection adjacent one end thereof with the hubs of bevel pinions 21 and 22. These pinions are of the same size and are in mesh with similar superposed pinions 23 and 24 which are carried upon a vertical shaft 25. It is to be noted that the pinions 23 and 24 are disposed similarly, whereby the shafts 13 and 14 will be rotated in the same directions upon rotation of the shaft 25 in either direction.

The shaft 25 is journaled in suitable bearings and its lower end is projected beneath the floor 26 of the car. On the projecting end of the shaft 25 is a bevel pinion 27 which is in mesh with a similar pinion 28 provided upon the inner end of a longitudinal horizontal shaft 29, the latter being journaled in depending bracket bearings 30 and carrying at its front end a bevel pinion 31 which is driven from a similar pinion 32, provided on the lower end of a vertical shaft 33, mounted in suitable bearings and extending through the floor 26.

Within the casing 35 is an indicating mechanism corresponding to the indicating mechanism shown in Fig. 2, and with which the shaft 33 coöperates, and to actuate the

said mechanism there is provided a manually operable crank handle 40.

By virtue of the provision of the two housings 7 and 7' and the connections between the reels 16 and 17 of the housing 7 and the shafts 13' and 14' of the housing 7' it is obvious that the elements of the last named housing are operatively connected with the elements of the first housing and that the said housings may be removed and interchanged with other housings in which the belts are printed with other matter without disturbing the arrangement of the operating elements.

15 An indicator constructed in accordance with the present invention is simple, comparatively inexpensive to manufacture and practical and efficient in use.

From the foregoing description, it will be seen that simple and efficient means are provided for accomplishing the objects of the invention, but while the elements herein shown and described are well adapted to serve the functions set forth, it is obvious that various minor changes may be made in the proportions, shape and arrangement of the several parts, without departing from the spirit and scope of the invention as defined in the appended claim.

20 30 What is claimed is:

In an indicator of the type set forth, a base for attachment to a wall, a vertical brace wall mounted at one end of said base,

said brace wall being formed with openings, said base being formed with a horizontal dove-tail groove extending between the ends thereof, two housings arranged side by side and each formed on their rear walls with tongues engaging said grooves, one of the housings bearing against said brace wall, 35 said housings each having their side walls formed with openings alined with the openings in said brace wall, upper and lower shafts journaled in the openings of each housing, the upper shafts having their adjacent ends keyed and the lower shafts having their ends similarly keyed, pinions carried detachably upon the ends of the upper and lower shafts of the housing that bears against the brace wall, said pinions having 40 their hubs disposed in the openings in said brace wall, gearing for driving said pinions at the same time and in the same direction, upper and lower winding reels carried by 45 said respective upper and lower shafts, and display belts trained over the respective pairs of upper and lower reels, said housings having their front walls provided with 50 openings to permit of reading said display belts.

55 In testimony whereof, I affix my signature, in presence of two witnesses.

60 HARRY M. BELL.
